UNITED STATES PATENT OFFICE.

CHESTER F. KROM, OF ST. PETERSBURG, FLORIDA.

DISPLAY CABINET.

Application filed May 19, 1922. Serial No. 562,261.

To all whom it may concern:

Be it known that I, CHESTER F. KROM, a citizen of the United States, residing at St. Petersburg, in the county of Pinellas and

5 State of Florida, have invented new and useful Improvements in Display Cabinets, of which the following is a specification.

The general object of this invention is to provide a cabinet adapted for displaying 10 bolts of laces and fine trimmings of all kinds. It is understood that usually the lace is wound upon card boards for facilitating the handling of the same. This of course requires constant handling thereof and subjects 15 the goods to great liability of damage.

It is one of the objects of this invention to obviate this fault by removing the card board and mounting the goods upon a detachable reel which is of such a construction 20 as to permit of the same to be adjusted to receive different sizes of bolts and which can be readily mounted within a frame, said frame being in turn slidably mounted in a cabinet.

25 Another object of the invention is to provide a frame which comprises two members which are pivotally secured together so that when the same is withdrawn from the cabinet the front section or member of the frame 30 will be adapted to swing to a substantially vertical position, thus permitting the reel which is mounted therein to be freely rotated.

In carrying out the objects of the invention generally stated above it will be understood, of course, that the essential features thereof are necessarily susceptible to changes in detail and structural arrangement, one preferred and practical embodiment being 40 shown in the accompanying drawings, wherein:—

Figure 1 is a front elevation of a cabinet, one of the frames being withdrawn therefrom so as to permit the goods to be unwound 45 from the reel.

Figure 2 is a fragmentary side elevation of a cabinet, partly broken away, showing the frame therein.

Figure 3 is a similar view showing the 50 frame withdrawn from the cabinet and in a position to permit the free rotation of the reel.

Figure 4 is a top plan view of the frame detached, showing the reel mounted therein.

55 Figure 5 is a fragmentary side elevation

of the frame, partly broken away, showing the means for retaining the reel in a horizontal position, when the frame is wholly within the cabinet.

Figure 6 is a fragmentary perspective 60 view of the reel.

Referring to the accompanying drawings by numerals, it will be seen that the invention comprises a cabinet 7 having a plurality of openings therein for the reception of 65 the frame which will be hereinafter more fully described. Arranged longitudinally of the side walls of the cabinet are a plurality of spaced parallel strips 8 and 9 in which the said frame is slidably mounted.

70 The supporting frame comprises a pair of substantially U-shaped front and rear members 10 and 11. The rear member 10 is contracted, as indicated at 12, and the ends 13 and 14 of said member are extended in 75 parallel relation to the longitudinal portions thereof. Catches 15 are pivoted to the rear of the member 10 by means of pivot pins 16 and said catches are adapted to engage in notches 17 formed in the strips 9 when the 80 frame is being withdrawn from the cabinet, thus preventing the entire withdrawal of said frame. The front member 11 is provided with an enlarged end 18 and said member has its free ends inturned and bent upon 85 itself to provide the arms 19 and 20.

75 The front member 11 is pivoted to the rear member 10 by means of the pivots 21 which engage the free ends 13 and 14 of the member 10 and the arms 19 and 20 of the member 90 11 intermediate the ends thereof. It will thus be seen that the longitudinal arms of the members 10 and 11 will be indirectly aligned with each other, thus permitting the frame to slide back and forth between the 95 strips 8 and 9.

Carried by the arm 20 intermediate the pivot 21 and the extreme end of said arm, and projecting laterally therefrom is a pair of lugs 22 and 23, said lugs being spaced 100 100 and one of them arranged on each longitudinal edge of said arm 20 for the purpose which will be hereinafter more fully described.

The reel upon which the bolt of goods is 105 wound and which is mounted in the frame consists of a pair of parallel side members 24 and 25, said members being formed preferably of one piece of material bent upon itself. Each of the side members are crimped 110

at their ends to provide a plurality of apertures 26 and are also crimped medially thereof, as indicated at 27, for a purpose which will be presently described. A stub shaft 5 28 is fixedly secured in the crimped portion 27 of the side member 25 and the free end of said shaft is mounted in alined transversed slots formed adjacent the extremities of the arms 14 and 19. The other side member 10 24 has fixedly secured therein at its crimped portion 27 a crank shaft 29 which is used for rotating said reel and which is wholly within the cabinet, thus preventing any possible rotation of said reel when the frame is 15 in the last named position. Adjacent the ends of the arms 14 and 20 the same are provided on opposite edges thereof with alined transverse slots 31 and 30, respectively, which are adapted to engage the crank shaft 20 29 to form a bearing therefor.

When it is desired to mount a bolt of goods upon the reel the card board is removed from said bolt and in its place are inserted the pins 32 with the ends thereof 25 projecting beyond the longitudinal edge of said bolt so that said ends may be inserted in any of the numerous apertures 26 in the side members 24 and 25. It will thus be seen that the reel is adapted to receive different lengths of bolts so that the same will 30 be tightly held thereon at all times. In order to display the different samples of goods, the free end may be passed around the front end 18 of the frame and secured to 35 the rear thereof by a longitudinally extending leaf spring 33 which is attached to said portion 18.

When it is desired to unwind a portion of the goods, the frame is withdrawn from the 40 cabinet until the catches 15 engage in the notches 17 and the front member 11 of said frame is then raised to a substantially vertical position. The movement of this member on its pivot 21 will permit of the disengagement of the lug 22 with the crank 29 and thus permit of a rotation of the reel by 45 means of said crank. It is to be noted that when the member 11 is raised the slot 30 in the arm 20 will disengage from the crank 29 50 and said crank will then have a bearing only in the slot 31 of the free end 14 of the member 10.

It will thus be seen from the foregoing that there has been provided a simple and 55 effective device for displaying the goods which are normally retained within the cabinet.

What I claim is:—

1. A device of the character described comprising a frame, said frame consisting of 60 front and rear U-shaped members, the free ends of said rear member being inbent, the free ends of said front member being in-turned and bent upon themselves, means for pivotally connecting said members so that the longitudinal sides thereof will be in direct alinement, a reel mounted in said frame, and means carried by the rear part of said frame for preventing rotation of said reel when the front member of the frame is 70 lowered.

2. A device of the class described comprising a frame consisting of front and rear U-shaped members pivotally connected to each other, a reel rotatably mounted in said frame, and means carried by said frame and engaging said reel to prevent rotation thereof when the members of said frame are in alinement, said means being adapted to disengage from said reel when one of the members is swung at an angle to the other, thereby permitting rotation of said reel. 80

3. A reel support including a frame comprising independent members, the side bars of one member being formed in returned members disposed fully between the side bars of the other member being inwardly and forwardly projected with relation to the frame to provide pivot arms, the side bars of the first named pivot arms, a pivot uniting said arms relatively remote from their free ends, the ends of the arms in advance of the pivot being formed to receive the reel, whereby in 90 the relative movement of the frames upon the arm pivots the reel is free for rotation.

4. A reel support including a frame made up of front and rear U-shaped members, the forward member having the terminals of its arms bent inwardly and forwardly to provide reel holding arms, the arms of the rear members being bent laterally and forwardly to provide pivot arms, the pivot arms of the rear member being arranged respectively in contact with and between the pivot arms of the outer member, and a pivot connecting the respective arms of each pair, the arms of the respective members being so spaced from the main arms of the member that said main arms are in alinement when 100 the members are in closed relation. 105

In testimony whereof I affix my signature.

CHESTER F. KROM.
